TOY EXCAVATOR SHOVEL

George A. Worrall, San Francisco, Calif.

Application February 4, 1946; Serial No. 645,348

2 Claims. (Cl. 46—40)

1

This invention relates to a toy excavator shovel, and one of the objects of the invention is to provide a toy shovel that simulates the large excavator shovels in appearance and action but that enables actuation of the dipper handle and dipper in a much faster and easier manner than heretofore.

Another object of the invention is the provision of a toy excavator shovel that includes a yieldably rocking frame mounting the boom and dipper handle, and which frame is rotatable for swinging the boom and dipper handle, including the dipper and controls for the handle and dipper, about a vertical axis, and which swinging may be effected by manipulation of said controls.

Heretofore in most toy excavator shovels of which I am aware, the dipper handle is actuated by a windlass that is connected with the handle of a flexible line inasmuch as this system in general, is the one actually used in large power shovels. However, the resulting actuation of the handle by this method is slow and the windlass may slip, releasing the handle prematurely, or if a ratchet and pawl means is used for the windlass, the same is expensive and subject to breakage and is difficult for very small children to manipulate properly. Furthermore, once the dipper handle and dipper are elevated the child must manipulate some other part of the toy to swing the same to the desired position for discharge of the load.

With the present invention the foregoing objections are overcome and the dipper may be elevated by manipulation of a simple lever that simulates the lever used on the actual shovels for controlling the windlass while a second similar lever may be manipulated to release the dipper for discharging its load. The lever for actuating the dipper handle also functions for swinging the latter so the child may very rapidly swing the dipper through a loading stroke and practically simultaneously swing the dipper about a vertical axis to an unloading position. The dipper handle is carried on a swinging frame that is also adapted to rock slightly as the dipper is loaded, much in the same manner as a large shovel, which adds to the child's interest in the toy.

Other objects and advantages will appear in the description and drawings.

In the drawings, Fig. 1 is a side-elevational view of the toy with the dipper in loading position, and in dot-dash lines an adjusted position of the dipper and handle is indicated. The

2

frame and base support for the shovel is broken away and partly in section to show internal structure.

Fig. 2 is a reduced fragmentary view indicating the dipper and handle in elevated position and showing the actuation of a lever for so elevating the same.

Fig. 3 is a view similar to that of Fig. 2, but showing the dipper lever in position releasing the dipper walls from material retaining position for discharge of the load.

Fig. 4 is a top plan view of the toy of Fig. 1.

In detail, the toy as illustrated comprises a horizontal base plate 1 having downwardly extending side flanges 2 that are apertured at their corners for passage of axles 3 therethrough, which axles carry ground wheels 4 thereon for supporting the base plate for movement over the floor or ground.

Above base plate 1 is a frame having a horizontal floor plate 5 that overlies the base plate. Opposed side walls 6 integral with said floor plate extend upwardly from two opposite edges of the latter, and a top strip 7 connects the side walls 6 at their upper ends. The strip 7 is about centrally disposed over the floor plate, and is relatively narrow, and the lateral edges of the side plates extend convergently to opposite edges of said strip as best seen in Fig. 1.

Floor plate 5 and the base plate 1 are coaxially apertured centrally thereof for passage of a vertical bolt 8, and a coil spring 9 around said bolt is positioned between the two plates. When nut 10 on bolt 8 is tightened to hold the spring 9 under compression (but slightly expanded) the plate 5 is adapted to rock slightly under a downward force on the frame that carries the floor plate applied at one side of the bolt 8. The bolt 8 also functions as a vertical pivot about which the floor plate may revolve relative to the base plate 1. The degree of tension on spring 9 determines the facility with which the floor plate may rock, as will later be explained more fully, it being sufficient at the present to note that the floor plate is yieldably held by spring 9 parallel with plate 1 and spaced above the latter.

A horizontal rod 15 is carried by side walls 6 at a point spaced above floor plate 5 and parallel with strip 7 at a point about directly below one of the longitudinal edges of said strip. Said rod is preferably closer to plate 5 than to strip 7 and is secured at its ends to said side walls 6 extending through the latter.

A boom generally designated 16, is preferably formed of a single strip of metal bent to gen-

erally U-shape, but with the end portions 17 of the legs thereof adjacent their free ends being more widely spaced than the portions 18 thereof adjacent their connected ends, as seen in Fig. 4. The portions 17 extend alongside side walls 6 and are apertured at their outer ends for rod 15 that extends through said ends. Rivets 20 spaced from the free ends of portions 17 secure the latter to said side walls, whereby the boom will be held rigid with said walls.

The rivets 20 are spaced above rod 15 and adjacent the strip 7 for supporting the boom in upwardly slanted position between vertical and horizontal so that its outer end projects laterally beyond the frame carrying floor plate 7 as well as beyond base plate 1.

A dipper handle 21 in the form of a channel strip, extends between the portions 18 of the outer end of boom 16, the sides of said strip being adjacent said portions 18. Said sides of the dipper handle are apertured at a point relatively close to one end 22 of the handle and relatively remote from the other end 23 thereof. The portions 18 of the boom are correspondingly apertured at a point adjacent the closed outer end of the boom and a pivot 24, which may be in the form of a cotter pin, extends through the said apertures in the handle and boom about which the handle is adapted to pivot.

The dipper handle 21 will automatically swing by gravity to a vertical position if no force is applied thereto, with the end 23 lowermost.

Said end 23 is preferably disposed at an angle to the remaining length of the dipper handle, and in a direction extending toward the wheel mounted base of the shovel when the handle is vertical. Carried on said end 23 and rigid therewith is a bottom wall 24' of a dipper. This bottom wall is preferably substantially parallel with said end 23 and has flanges 25 at its opposite edges that extend from the side of the bottom opposite end 23, said flanges being in planes parallel with the sides of the dipper handle.

The remainder of the dipper comprises an end wall 26 that is adapted to extend parallel with the outermost end edge of bottom 24' and over said bottom when the dipper is closed. Side walls 27 extend at right angles to said end wall from its end edges and are integral with said end wall. These side walls are in planes parallel with flanges 25 and preferably extend alongside the inner opposed sides of said flanges. Pivots 28 connect said side walls with said flanges at the ends thereof that are nearest the pivot 24 and which ends are at about the juncture between the angularly extending end 23 of the dipper handle and the straight length thereof that extends from end 23 to said pivot 24. Thus the end wall 26 can be swung away from the adjacent edge of the bottom wall 24' about pivots 28, which pivots are coaxial.

Extending between side walls 27 of the dipper is a cross piece 30 (Fig. 4) provided with an eye 31 intermediate its ends. The ends of said cross piece pivotally extend through said side walls 27 at points adjacent the free edges of side walls 27, but spaced outwardly of pivots 28 with respect to bottom wall 24'.

A pair of vertically extending levers 35, 36 are pivotally supported at their lower ends on rod 15 adjacent the opposite ends of said rod. A spacer tube 37 on said rod and between the lower ends of said levers holds the latter spaced from each other.

When said levers extend vertically upwardly

from rod 15 they are adapted to engage the edge of strip 7 that faces away from the boom 16, which strip prevents the levers from swinging past the same in the direction of the boom, although said levers may be swung in the opposite direction until they extend generally horizontally and until they strike the floor plate 5.

A flexible line in the form of a chain 38 connects with lever 36 at one of its ends at a point 10 on said lever adjacent its upper end, and the opposite end of chain 38 connects with the outer end of the short portion 22 of the dipper handle. A handle knob or enlargement 39 on the upper end of lever 36 facilitates the engagement by 15 the upper end of said lever with the child's hand.

As previously stated, the dipper handle tends to swing automatically by gravity to vertically extending position with the dipper lowermost or on the ground, and with the short end portion 22 projecting upwardly from the outer end of the boom. The chain 38 connecting said end portion 22 with the lever will hold the lever vertically and against strip 7. Upon the child's grasping the knob 39 on lever 36 and swinging 25 said lever to horizontally extending position, as seen in Fig. 2, the dipper handle 21 will be swung through a digging arc to horizontally extending elevated position and will be ready for swinging of the boom about pivot 8 to any desired position for releasing the dipper and unloading its contents.

The eye 31 of cross piece 30 that is on the dipper is connected with the upper end of lever 35 by a chain 40, which chain slidably extends over 35 the pivot pin 24 that pivotally supports the dipper handle. A knob or handle 41 similar to handle 39 is on the upper end of lever 35.

When the dipper handle is elevated the sides 27 and end wall 26 thereof are supported on the bottom wall 24, thus coacting with the bottom wall for forming a receptacle for the material being dug by the dipper. If, as in Fig. 1, the dipper should be open when the cutting stroke starts, it will automatically close before the dipper leaves the ground and before any material can escape therefrom.

When the dipper handle is in the horizontally extending position seen in Fig. 2, a swinging of lever arm 35 downwardly to a position even with 50 lever 36 will pull the dipper open, releasing the material therein for dumping as seen in Fig. 3.

It is pertinent to note that when the lever 36 is in the position seen in Fig. 2 and the dipper handle is elevated, the child may swing the boom and frame carrying it in any direction about pivot 8 merely by swinging the lever 36 laterally. In other words, the hand that swung the lever downwardly can then swing laterally for swinging the boom without necessitating a new grip being taken or without requiring the use of the other hand of the child.

This feature and the fact that the levers 35, 36 simulate the levers on a large power shovel, make the present invention particularly attractive to 65 children. In power shovels, in so far as children are concerned, the windlass is relatively unimportant. They see the operator pull a lever, whereupon the dipper handle swings upwardly. He may pull another lever and the dipper releases its load. In the present invention these results also occur, but without the complicated intervening parts that are of no interest to the child.

The spring 9 between the floor plate 5 and the 70 base plate 1 keeps the floor plate away from the

base plate during swinging of the boom, and when a load is being dug by the dipper, the floor plate will yieldably tilt as in large power shovels, thus simulating the action of the large shovels. Also this yieldable movement reduces the shock on the base plate where rocks are encountered during the digging stroke.

The dipper handle may have additional openings 50 therein for the pivot 24, thus enabling the shovel to hang in the position shown at 51 in dot-dash line and also changing the stroke of the dipper.

The detailed description and drawings are not to be considered restrictive of the invention, but merely illustrative of a preferred form thereof.

I claim:

1. A toy excavator shovel comprising a wheel mounted base plate, a frame above said plate vertically pivoted to the latter for swinging about a vertical axis, a vertically extending lever pivotally secured to said frame at its lower end at one side of said axis for downward swinging of its upper end in a direction away from said axis, a boom rigid on said frame extending slantingly upwardly and outwardly therefrom at the opposite side of said axis and in a direction directly opposite to the direction of swing of said lever, a vertically extending dipper handle pivotally secured at a point intermediate its ends to the outer end of said boom, a dipper secured to the lower end of said handle, a flexible line connecting the upper end of said lever with the upper end of said handle for swinging said handle upon said downward swinging of the upper end of said lever, said lever being positioned for downward swinging to generally horizontal position with its upper end projecting from the side of said frame opposite said boom to enable a child outwardly of the side opposite said boom to swing said frame including the boom about said axis by said lever.

2. A toy excavator shovel comprising a base plate having ground wheels secured thereto, a frame above said plate vertically pivoted to the latter for swinging about a vertical axis, a pair of vertically extending levers pivotally secured to said frame at their lower ends at one side of said axis for downward swinging of their upper ends in a direction away from said axis, a boom on said frame extending slantingly upwardly and outwardly from said frame at the other side of said axis, a vertically extending dipper handle pivotally secured at a point intermediate its ends to the outer end of said boom, a dipper secured to the lower end of said handle having a wall movable relative to said handle for releasing the contents of the dipper, a pair of flexible lines respectively connecting the upper ends of said levers with the upper end of said handle and with said wall for swinging said dipper handle and for causing said movement of said wall upon said downward swinging of the upper ends of said levers, said levers being positioned for swinging downwardly to generally horizontally extending positions with their upper ends projecting from the side of said frame opposite said boom to enable a child to swing said frame about said axis by either or both of said levers.
